UNITED STATES PATENT OFFICE.

BERYL V. BOOTH, OF AKRON, OHIO.

PUNCH BOWL.

Application filed July 13, 1923. Serial No. 651,207.

This invention relates to liquid containers and is herein shown as embodied in a punch bowl, but this invention in many of its features is not limited to containers of this 5 particular type but may readily be adapted to containers of various types.

A broad feature of the present invention consists in a novel organization and arrangement of a cooling system with a punch 10 bowl whereby the liquid contained therein will be automatically cooled in an efficient and effective manner.

One of the objects of the invention is to provide an efficient substitute for the usual 15 "snow bank" which is used not only to keep the contents of the punch bowl chilled, but to add to the attractiveness of the display and thus assist in the sales of the punch.

An objection to the usual snow bank has 20 been the consequent melting of the snow which has rendered it somewhat expensive and unsuited for location in certain places, such as, for example, in department stores. By my invention, however, a snow bank is 25 maintained about the punch bowl without the disadvantages of the melting ice or snow.

These and many other important features of this invention will appear from the 30 following description read in conjunction with the accompanying drawings and will be particularly pointed out in the claims.

In the drawings:

Figure 1 is a side elevation of the bowl selected to illustrate this invention;

35 Figure 2 is a plan view thereof;

Figure 3 is a vertical section on line 3—3 of Figure 2; and

40 Figure 4 is a horizontal section on line 4—4 of Figure 3, part of the bowl being shown in plan.

The illustrated punch bowl comprises a supporting tray 2 having a bottom 4, a base rim 6 and concavo-convex sides 8 flared outwardly to provide an enlarged mouth 10 at the top of the tray. Within the tray and spaced from the sides and bottom thereof is an inner wall 12 sealed to the sides of the tray at 14 to form an air-tight compartment 16 which serves as a heat insulator for 45 a purpose to be presently apparent. A spacer block 18 is located between the inner wall 12 and the bottom 4 of the tray.

50 Centrally located within the supporting tray 2 is a bowl shaped liquid cooling vessel 20 of any suitable material, which may

be glass to give color to the frost bank F. The top of the vessel is closed by semi-circular cover plates 22 suitably hinged at 24 to a stationary cross bar 26. Extending downwardly from the bottom 28 of the cooling vessel is a circular base flange 30 adapted to support the vessel above the tray 2.

Spirally arranged around the sides of the vessel 20 is a cooling coil 32 through which 60 a suitable cooling medium is forced, the latter being led into the coil by an inlet pipe 34 connecting with a convenient source of supply and leaving the coil through an outlet pipe 36, both the inlet and outlet 65 pipes extending through suitable apertures provided in the bottom of the supporting tray. The coil 32 is supported by a plurality of metallic plates 36 to which the turns of the coil are soldered, the plates 70 being secured to the inner surface of the tray in any suitable manner.

Completely surrounding the coils and cooling vessel and spaced therefrom is an enclosure 38 consisting of a plurality of 80 arc-shaped glass plates 40 having the adjacent edges thereof spaced, as at 42, to afford passageways for the admission of air to the coils. The glass plates 40 are retained in position by upper and lower 85 retaining rims 44 semi-circular in cross-section and arranged to receive the plates therebetween, the bottom retaining rim being supported upon the inner surface of the tray 2.

The top of the enclosure 38 is covered by 90 a glass plate 46, preferably formed in two sections 48 and 50 connected together by suitable straps 52. The cover plate 46 has a central opening 54 formed therein of sufficient size to snugly receive the cooling vessel 20, the inner edges of the plate being adapted to engage the flange rim 56 on the top of the vessel. The cover plate 46 is supported by the side plates 40, a plurality 95 of distance members 48 being interposed between the under surface of the plate and the plates to elevate the former and provide passages for the entrance of air to the coils.

From the above description it will be evident that the temperature of the cooling vessel will be maintained at a low point through the medium of the cooling coils 32. The vessel 20 and cooling coils 32 are substantially completely surrounded by insulat- 105 110

ing elements which prevent the entrance of heat and temperature elevating air currents. However, the provision of the passageways 42 between the side enclosure plates, and the 5 enclosure plates and the cover 46 permits the admission of a slight amount of air to the coils and the humidity of the atmosphere will cause the formation of a layer of frost around the coils which will greatly increase 10 the efficiency thereof.

In the use of the above device, it has been found that some condensation will take place within the enclosure 38 and, accordingly, provision is made by which the products 15 of condensation are removed. A central opening 60 is formed in the bottom of the tray 2 and the spacer block 18 to receive a drain pipe 62. Above the opening 60 upon the inner surface of the tray is a deflecting 20 member 64 having its sides 66 secured to the bottom of the tray 2 to effectively prevent the entrance of warm air through the drain pipe. The bottom edge of the deflecting member 64 is provided with a plurality 25 of slots 68 through which the condensation products within the enclosure 38 escape to the drain pipe. The member 64 has an additional function of serving to locate the vessel relative to the supporting 30 tray by engagement with the base flange 30 of the cooling vessel.

It will be observed that by enclosing the bowl and the coils within glass the frost, indicated by the letter F, will be entirely 35 protected from drafts which tend to melt it away, while the slight apertures provided between the glass pieces and under the cover 46 permit access of sufficient air to build up the frost bank which shows through the glass 40 and gives a cool and attractive appearance to the punch bowl. It is unnecessary to provide the usual "snow bank" and the same or a better effect is obtained.

I have herein disclosed my invention in 45 connection with one embodiment thereof, selected for illustrative purposes only. Obviously, my invention is not restricted to this particular embodiment.

Having described my invention, what I 50 claim as new and desire to secure by Letters Patent of the United States is:

1. A punch bowl having a cooling compartment, an enclosure surrounding said compartment and spaced therefrom, and a 55 cooling coil within said enclosure surrounding the compartment, said enclosure being provided with air inlets.

2. A punch bowl having a cooling compartment, and an enclosure surrounding said compartment and spaced therefrom, said enclosure comprising a plurality of arc-shaped sections having air passageways between the adjacent sections.

3. A punch bowl having a cooling compartment, a sectional enclosure surrounding

said compartment and spaced therefrom, and a cooling coil within the enclosure and surrounding the compartment, the sections of the enclosure being spaced to afford passageways therein.

70

4. A punch bowl having a cooling compartment, an insulating enclosure surrounding said compartment and spaced therefrom, and a cooling coil within said enclosure, the said enclosure being provided 75 with air passages in the top and sides thereof.

5. A punch bowl having a cooling compartment, a tray adapted to receive and support said compartment, a protecting enclosure surrounding said compartment, and a cooling coil carried by said tray and adapted to encircle said compartment, the said enclosure being provided with a plurality 80 of air inlets.

85

6. A punch bowl comprising a support, a cooling compartment mounted on said support, an enclosure resting on said support and surrounding said compartment, said enclosure consisting of a cover plate provided 90 with a central opening to receive the cooling compartment and a plurality of side sections, the said sections being spaced from one another and from the cover plate, a spiral cooling coil within the enclosure and 95 encircling the cooling compartment, means for supporting the cooling coil, and a drain pipe extending through the bottom of the support.

100

7. A punch bowl comprising a supporting tray, an insulating jacket within said tray, a cooling compartment centrally mounted within the tray, an enclosure surrounding said compartment and spaced therefrom, said enclosure including a plurality of arc-shaped side plates resting upon the inner surface of the supporting tray, retaining rims having recesses therein to receive the top and bottom edges of the plates, the said side plates being spaced from one another, a top cover plate, means for spacing the cover plate from the side plates, a spiral cooling coil within the enclosure and surrounding the cooling compartment, a plurality of arms for supporting the said coil, 110 a drain pipe extending through the bottom of the supporting tray, and means for covering the drain pipe, said latter means being provided with passageways connecting the enclosure with the drain pipe.

115

8. A punch bowl having a cooling compartment, an enclosure surrounding said compartment, means located within the enclosure for chilling it, there being provided means to maintain a humid gas in the interior of the enclosure whereby a frost bank will be formed therein.

120

9. A punch bowl having a cooling compartment, an enclosure surrounding said compartment and spaced therefrom, means 125 to maintain a humid gas in the interior of the enclosure whereby a frost bank will be formed therein.

130

- to chill the air within the enclosure and means for maintaining a humid gas in the interior of the enclosure so that a frost bank will accumulate therein.
- 5 10. A punch bowl comprising a tray, a heat insulating means in the base of the tray, a bowl located within the tray, an enclosure supported upon the tray and surrounding but spaced from the bowl, a cooling coil within the enclosure, said coil having inlet and outlet pipes passing through the bottom of the tray, means for maintaining a humid gas about said coil, and a cover above the enclosure and surrounding the bowl.
- 10 11. In a dispensing device, outer and inner bowls and a refrigerating coil about the inner bowl, and a transparent casing about said coils.
- 15 12. In a dispensing device, outer and inner bowls and a refrigerating coil about the inner bowl, and a transparent casing about said coils, said casing resting in said outer bowl.
13. The combination with a counter and a dispensing bowl, of a refrigerating coil, enclosing the sides of said bowl, and a transparent casing forming a refrigerating chamber about said bowl.
14. In a dispensing device, a counter, outer and inner bowls thereon, said outer bowl serving to receive the drip from the inner bowl, a refrigerating coil about said inner bowl, a transparent refrigerating chamber enclosing said coils, and means for maintaining a low degree of temperature in said coils.
15. A liquid chilling device having a receptacle for the storage of liquid, an enclosure surrounding the receptacle but spaced therefrom to provide a cooling compartment, and coils located within the compartment, said coils being adapted for the circulation of a refrigerant, there being provided means to maintain a humid gas in the interior of the compartment whereby a frost bank will be formed upon the exterior of the coils.

BERYL V. BOOTH.
